US00D945981S

(12) **United States Design Patent** (10) **Patent No.:** **US D945,981 S**
(45) **Date of Patent:** **** Mar. 15, 2022**

(54) **AUDIO HEADPHONES**

(71) Applicant: **Stephen John Rois**, St. Louis, MO (US)

EM 0080233450002 6/2020

(72) Inventor: **Stephen John Rois**, St. Louis, MO (US)

FOREIGN PATENT DOCUMENTS

(**) Term: **15 Years**

U.S. Appl. No. 29/721,807, filed Jan. 23, 2020.

(21) Appl. No.: **29/807,530**

OTHER PUBLICATIONS

(22) Filed: **Sep. 13, 2021**

Primary Examiner — Paula Allen Greene

(74) Attorney, Agent, or Firm — Harness, Dickey & Pierce, P.L.C.; Anthony G. Fussner

(57) **CLAIM**

The ornamental designs for audio headphones, as shown and described.

DESCRIPTION

(62) Division of application No. 29/721,807, filed on Jan. 23, 2020, now Pat. No. Des. 933,041.

FIG. 1 is a front perspective view of audio headphones showing the new design;

(51) **LOC (13) Cl. 14-01**

FIG. 2 is a perspective view thereof;

(52) **U.S. Cl.**

FIG. 3 is a perspective view thereof;

USPC **D14/205**

FIG. 4 is a perspective view thereof;

(58) **Field of Classification Search**

FIG. 5 is a front view thereof;

USPC D14/205, 206, 188, 192; D29/112;

FIG. 6 is a back view thereof;

2/209; 381/380, 381, 370, 371, 372;

FIG. 7 is a right side view thereof;

455/90.3, 575.1, 569.1

FIG. 8 is a left side view thereof;

CPC H04R 25/00; H04R 25/02; H04R 1/1066;

FIG. 9 is a top view thereof;

H04R 1/1016; H04R 5/033; H04R

FIG. 10 is a bottom view thereof;

5/0335; H04R 1/10; H04R 1/105; H04R

FIG. 11 is a perspective view of a second embodiment of

1/008; H04R 1/1083; H04R 1/1091

audio headphones showing the new design;

See application file for complete search history.

FIG. 12 is a perspective view thereof;

(56) **References Cited**

FIG. 13 is a perspective view thereof;

U.S. PATENT DOCUMENTS

FIG. 14 is a perspective view thereof;

3,073,410 A * 1/1963 Gongoll H04R 1/1008
2/209

FIG. 15 is a left side view thereof;

3,141,221 A 7/1964 Faulls, Jr.

FIG. 16 is a right side view thereof;

3,220,505 A * 11/1965 Hargrave H04M 1/05

FIG. 17 is a front elevational view thereof;

181/129

FIG. 18 is a rear elevational view thereof;

D215,375 S 9/1969 Doggett

FIG. 19 is a side elevational view thereof; and,

D227,742 S 7/1973 Logsdon

FIG. 20 is a side elevational view thereof.

(Continued)

The broken lines depict portions of the audio headphones that form no part of the claimed design.
